(57) **CLAIM**

The ornamental design for a wireless charger, as shown and described.

DESCRIPTION

FIG. 1 is a front, left, top perspective view of a wireless charger, showing my new design;

FIG. 2 is a front, left, top perspective view of a reduced scale thereof, shown from another angle;

FIG. 3 is a rear, left, bottom perspective view of an enlarged scale thereof;

FIG. 4 is a front elevational view of a reduced scale thereof;

FIG. 5 is a rear elevational view of a reduced scale thereof;

FIG. 6 is a left side view of an enlarged scale thereof;

FIG. 7 is a right side view of an enlarged scale thereof;

FIG. 8 is a top plan view of a reduced scale thereof;

FIG. 9 is a bottom plan view of a reduced scale thereof;

FIG. 10 is an enlarged view of detail 10 in FIG. 1;

FIG. 11 is an enlarged view of detail 11 in FIG. 1;

FIG. 12 is an enlarged view of detail 12 in FIG. 2; and,

FIG. 13 is an enlarged view of detail 13 in FIG. 8.

The dashed broken lines in the figures illustrate portions of the wireless charger that form no part of the claimed design. The dash-dot-dash broken lines are for notating enlarged views and form no part of the claimed design.
